UNITED STATES PATENT OFFICE.

JESSE G. POPPERT, OF MILWAUKEE, WISCONSIN.

CIGAR-HOLDER AND ASH-RECEPTACLE.

SPECIFICATION forming part of Letters Patent No. 785,377, dated March 21, 1905.

Application filed March 14, 1903. Serial No. 147,867.

To all whom it may concern:

Be it known that I, JESSE G. POPPERT, a citizen of the United States, residing at Milwaukee, county of Milwaukee, and State of Wisconsin, have invented new and useful Improvements in a Combined Cigar-Holder and Ash-Receptacle, of which the following is a specification.

My invention relates to improvements in combined cigar-holders and ash-receptacles.

The object of my invention is to provide a light and neat attachment for cigars which will catch the ashes of the cigar and prevent them from falling, whereby the danger and annoyance arising from the falling of fire and ashes from a lighted cigar when being smoked upon the clothes of a person or the furniture of a room is avoided and the objection to smoking indoors for such reasons is largely overcome.

The construction of my invention is explained by reference to the accompanying drawings, in which—

Figure 1 represents a side view. Fig. 2 represents a top view. Fig. 3 is a side view of a modified form of construction. Fig. 4 is a longitudinal section of a modified form shown in Fig. 3. Fig. 5 is an end view, and Fig. 6 is a transverse section drawn on line xx of Fig. 1. Fig. 7 is a transverse section drawn on line xx of Fig. 3. Fig. 8 is a transverse section drawn on line yy of Fig. 4.

Like parts are identified by the same reference-letters throughout the several views.

35 A is a cigar.

B is a receptacle to which the cigar is attached by the clamping-arms C and D. The clamping-arm C is rigidly connected to the end of the tray by the bracket E, while the 40 other clamping-arm, D, is connected to the arm C by the parallel arms F and G and pivotal bolt or pin H. The lower ends of the arms C and D are thrown apart by the spring I, the central portion of which spring is coiled 45 around the pin H in such a manner that the recoil of the spring has a tendency to throw the lower ends of the clamping-arms against which they bear apart and their upper ends together around the cigar.

50 To prevent the ashes which accumulates in

the receptacle B from escaping from the end of the receptacle, as they might otherwise do when the person using the same inclines forward, I preferably provide the front or outer end of the receptacle with an inclosing end 55 piece J, which covers the ends of the cigar and prevents the ashes from escaping, as stated.

In the modified form shown in Figs. 3 and 4 K represents the ash-receptacle, and L the 60 cover. The cover L is adapted to partially surround the receptacle K and may, if desired, be turned on its longitudinal axis, so as to entirely inclose the upper side of the receptacle, as indicated in Figs. 3 and 7, whereby the 65 receptacle, together with the cigar, may, if desired, be placed in a person's pocket. The cover L is provided with a plurality of apertures P to permit of the circulation of air to and from the receptacle when the cover is in 70 the closed position. The respective ends of the cover L are cylindrical in shape, whereby they form retaining-bands which entirely surround the receptacle K and serve to hold the cover in place. The front end of the cover L 75 is open, and the bracket E is connected with the end of the receptacle K.

I am aware of the fact that closely-fitting ash-receptacles have previously been used in connection with cigars while being smoked; 80 but in such case the receptacle becomes heated to a high temperature in a few moments time and is liable to burn the fingers of the person using the same, while by my form of construction shown the cigar is supported above 85 and entirely free from contact with the receptacle itself, whereby the receptacle does not become heated and the danger of burning the fingers of the smoker is thereby avoided.

Having thus described my invention, what I claim as new, and desire to secure by Letters Patent, is—

1. The device herein described for catching and retaining the ashes of a cigar while being 95 smoked consisting in the combination of a receptacle open on one side for a portion of its length, clamping-arms C and D, arm-supporting bracket E rigidly connected with and projecting from the rear vertical end wall of said 100

receptacle; means for connecting said clamping-arms to said bracket, and means for holding said clamping-arms yieldingly against the cigar while the same is being smoked, said arms being adapted to support the cigar above, and free from contact with said receptacle, substantially as, and for the purpose specified.

2. A cigar attachment for catching and retaining the ashes of a cigar while being smoked, consisting in the combination of a cylindrical-shaped ash-receptacle open on one side for a portion of its length; a cylindrical-shaped inclosing cover open on one side for a

portion of its length connected with the periphery of said ash-receptacle and adapted to be turned on its longitudinal axis from a closed position above the mouth of said receptacle, partially around, and beneath the same, and means for clamping said receptacle to a cigar, substantially as, and for the purpose specified. 15

In testimony whereof I affix my signature in the presence of two witnesses.

JESSE G. POPPERT.
